UNITED STATES PATENT OFFICE.

CHARLES O. BAXTER, OF ST. LOUIS, MISSOURI.

KNOCKDOWN PICTURE-FRAME.

SPECIFICATION forming part of Letters Patent No. 351,955, dated November 2, 1886.

Application filed September 18, 1885. Serial No. 177,473. (No model.)

To all whom it may concern.

Be it known that I, CHARLES O. BAXTER, of the city of St. Louis, in the State of Missouri, have invented a certain new and useful Improvement in Knockdown Picture-Frames, of which the following is a full, clear, and exact description, reference being had to the accompanying drawings, forming part of this specification, and in which—

10 Figure 1 is a back view of my improved frame, with part of the picture broken away for exhibiting the rabbets of the end pieces, the inner portions of the mortises for permitting longitudinal play of the tenons of the end pieces also being shown in this view. Fig. 2 is a detail view showing one corner of the frame disjoined. Fig. 3 is a back view showing the two end pieces of the frame. Fig. 4 is a view of the end pieces rolled or folded together. Fig. 5 is an end view of same. Fig. 6 is a view of the side pieces placed together and the tightening cord or wire wrapped around them. Fig. 7 is a view of the side pieces and end pieces placed together in shipping position.

15 The object of my invention is to produce a knockdown picture-frame, or a frame that can be readily unfastened for detaching or separating it for shipment, and as readily put together again for use. It is more particularly intended to be applied to frames such as are used for show-cards and advertising purposes.

20 My invention relates to picture or show-card frames so constructed that they can be readily knocked down or unfastened for detachment and separation, and subsequently put together again; and my invention consists in features of novelty hereinafter fully described, and pointed out in the claims.

25 Referring to the drawings, A represents the side pieces, and B the end pieces, of the frame, both the side pieces and end pieces being provided preferably with rabbets C. They are preferably jointed by mortises D in the side pieces and tenons E, formed upon the end pieces when the frame is put together.

30 F represents the mount, consisting of a picture or show-card, which is glued or otherwise secured either to the side pieces or to the end pieces, but preferably to the latter, as shown

in Fig. 3; but it is not secured to the other pieces of the frame. In case it is secured to the end pieces, as shown, it is not secured to the side pieces, so that the side pieces can be removed from the end pieces without destroying the picture. If the picture should be secured to the side pieces, then it would not be secured to the end pieces, so that the end pieces can be removed without injury to the picture.

35 We will suppose that the picture is secured to the end pieces, as shown, and describe the manner of putting the frame together.

The end pieces have pins or brackets G, against which bear the free ends of levers H, pivoted to the side pieces, A. (See Fig. 1.) The inner ends of the levers are connected to a suitable tightening device, K, by ropes or wires N, as shown in Fig. 1; or they may be connected together in pairs, if desired, instead of all four being connected to one device.

40 I have shown the device consisting of a disk provided with an arm, L. By turning the disk, as shown in Fig. 1, the ropes or wires are tightened, causing the free ends of the lever to push against the pins on the end pieces of the frame, and thus by forcing the end pieces away from each other will stretch the picture and make it tight in the frame. When the disk is turned, the arm L is hooked over one of the ropes or wires, as shown, holding the parts 45 rigidly to their adjustment, and when the parts are thus held in place the picture is as firmly held in the frame as if put in in an ordinary way.

45 By simply loosening the tightening device the side pieces of the frame can be removed from the end pieces and placed together, as shown in Fig. 6, with the tightening-rope wound around them. The end pieces can be rolled together, as shown in Figs. 4 and 5, 50 with the picture wound around one of them, and the side pieces and end pieces are then put together, as shown in Fig. 7, making the whole frame a compact bunch, occupying very little space, thus greatly reducing the cost of 55 transportation and taking much less room for storage. When the frame reaches its destination, it can be quickly put together by any inexperienced person.

55 The levers H at one end of the frame could 60

be dispensed with and the levers at the other end connected by a suitable tightening device. In this case only one end of the frame will be moved to tighten the picture when the frame is put together.

I claim as my invention—

1. A knockdown picture-frame consisting of two opposite pieces connected together by a mount, and two opposite pieces provided with a tightening device by which the frame is held together, substantially as set forth.

2. A knockdown picture-frame consisting of end pieces, side pieces, mount connecting two opposite pieces, and a tightening device by which the pieces are held together, substantially as described.

3. A knockdown picture-frame consisting of end pieces, side pieces, a mount connecting two opposite pieces, and a tightening device comprising pins or projections, levers, and means for causing the levers to bear on the pins for holding the parts together, substantially as described.

4. A picture-frame consisting of the end pieces provided with pins or projections, the side pieces provided with pivoted levers, and a tightening device, substantially as described.

5. A picture-frame consisting of the end pieces, a mount secured to the end pieces, pins or projections on said end pieces, side pieces, levers pivoted to the side pieces, and a tightening device, substantially as described.

6. The combination of the end pieces provided with pins, and a mount secured to the same, tenons formed upon the ends of said end pieces, side pieces having mortises to receive the tenons, levers pivoted to the side pieces, and tightening device, substantially as described.

CHARLES O. BAXTER.
